UNITED STATES PATENT OFFICE.

EDWARD F. MALOUF, OF MARYSVILLE, CALIFORNIA.

NAIL SETTER.

Application filed February 12, 1927. Serial No. 167,743.

My invention relates to nail setters adapted for setting nails at predetermined spots, and it appertains particularly to nail setters adapted for the use of workmen, such as shoe makers, cobblers, shinglers, carpet and linoleum layers, or others, who are required to set a quantity of nails or tacks of the same kind.

The main object of the invention is to provide a nail setter, which is adapted to receive a number of nails therein and to be moved to a nail-setting position and held and manipulated by one hand of an operator so as to cause the nails to be conveyed one at a time to the setting position, while the operator's other hand is free to set the nails with a hammer. The invention thus substitutes a safe method of nail-setting for the prevailing practice among workmen to take a number of nails in the mouth, a practice often resulting in injury to the teeth of the workman and causing the workman to swallow some of the nails so that his health is thereby jeopardized.

Another important feature of the invention is to provide means for yieldingly holding a nail in the nail setter in order that, when the nail is placed in the setting position on an object, the operator may be able by contacting the point of the nail with the surface of the object to slide the nail so that the head thereof is pushed out of contact with the nail setter and therefore the nail can be hit with a hammer without liability to injury of the nail setter.

A further object is to provide a nail setter with means for yieldingly retaining the nails therein, so that, when the nails are released from the means for holding them in the position for setting, they may also be easily freed from the nail setter without causing injury to the latter.

A still further object is to provide a nail setter with means for adjusting it so as to accommodate nails or tacks of different thickness.

Another feature of the invention is to provide a nail setter with a guide member adapted to engage the edge of an object so that the nail setter may be moved along the edge for setting nails at predetermined spots on the object.

Still further objects and features will appear from the following detailed description, having reference to the accompanying draw-

ings, in which a preferred embodiment of the invention is illustrated and in which:

Figure 1 is a side elevation of the nail setter, with the operating parts thereof in their normal positions, the nail receptacle being shown with a cover therefor;

Figure 2 is a plan of the nail setter, with the operating parts in the positions shown in Figure 1, and with the guide member in engagement with the edge of a shoe sole, which is indicated by a dot-and-dash line, while the predetermined spots, at which the nails in the nail setter may be set, are indicated by a dotted line, the receptacle cover being broken in order to show underlying parts;

Figure 3 is a plan of the nail setter, with a portion of the nail conveyor in section in order to show clearly the bars that operate so as to allow only one nail at a time to pass through the conveyor, the bar nearest to the nail receptacle having been moved by the sliding movement of the receptacle so that it retains the nails in the conveyor, while the other bar at the same time has been moved so as to allow one nail to pass to the free end of the conveyor, where it is held by the nail-holding member, preparatory to the setting of the nail;

Figure 4 is a side elevation of the nail receptacle and a portion of the nail conveyor, and the means for spacing the conveyor members from each other, and also the supporting plate for the receptacle and the conveyor, the supporting plate being broken away in the middle, and the conveyor member nearest to the supporting plate being partly in section in order to show clearly the connection of the receptacle walls with the respective conveyor members;

Figure 5 is a sectional elevation taken along the line 5—5 in Figure 2, the handle for the nail setter being broken, and the lower part of the frame being omitted; and

Figure 6 is a sectional view taken along the line 6—6 in Figure 3, the view showing the screw with the taper end for adjustably separating the bars in the nail conveyor, and the spring that urges the bars into a yielding contact with the taper end.

In the drawings the complete nail setter of my invention is indicated by the numeral 1. This nail setter comprises a frame 2, which includes a handle 3 fixed to one end of the frame by any suitable means. At the

other end of the frame is a guide member 4, which is preferably provided with a stem 5 adapted to be threaded into the frame so as to be adjustably secured thereto. By this arrangement an operator may take hold of the handle and, after placing the frame upon an object so that the guide member contacts one edge of the object, may thereby move the nail setter along the edge, which in Figure 2 is indicated by a dot-and-dash line as being the edge of a shoe sole, for setting nails at predetermined spots on the sole, as indicated by a dotted line in the same figure.

The handle 3 is preferably hollow and has adjustably secured therein the shank of a mounting member 6 by screws 7, and to the head of this mounting member is fixed a bar 8, which extends with its major portion in the general direction of the frame 2. Upon the mounting member 6 are also fixed guide plates 9 and 10, each of which is provided with an opening 11 for slidably receiving an operating rod 12 therein, and other plates 13 and 14 are respectively attached to the guide plates 9 and 10 for retaining the rod 12 in the opening 11 of the guide plates. A compression spring 15 is coiled around the operating rod outside of the plate 10, and the rod is at this end provided with a push plate or button 16 for moving the rod against the tension of the spring, a pin 17 being preferably provided for engaging one end of the spring while the other end thereof contacts the plate.

The nail setter 1 further comprises a nail receptacle 18 consisting of wall portions 19 and 20 and having the portion 19 provided with end wall additions 21, which converge toward the bottom of the receptacle, and the side portions of the receptacle are preferably correspondingly inclined toward the bottom of the receptacle. A nail conveyer 22 consisting of a pair of suitably formed members 23 and 24 adapted to extend alongside of, and to be spaced from each other, has the members 23 and 24 respectively connected with the wall portions 19 and 20 of the nail receptacle. This connection between the nail receptacle and the nail conveyer may be made in any suitable manner and preferably so that the receptacle is removable from the nail conveyer whenever it is so desired. As a means of accomplishing this result, I may provide each of the wall portions 19 and 20 with dowels 25, which fit in registering holes in the respective conveyer members, as shown in Figure 4.

For adjustably attaching the conveyer members 23 and 24 to each other, blocks 26, arranged in pairs, may be secured to the members by any suitable means, such as screws 27, and a plate 28, having slots 29 therein, is provided so that the nail receptacle 18 and the nail conveyer 22 may thereby be mounted on the plate with a certain degree of adjusta-

bility and firmly secured to the plate by the respective screws 27 in the conveyer member 24. In each pair of blocks 26 one of the blocks preferably has a dowel 30 fixed therein, while the other block has a corresponding hole for slidably fitting the block on the dowel. Also, a screw 31 is shown as being threaded through one block in each pair, while the other block in the pair is drilled for clearance of the screw, and around the screw and between the two blocks in each pair is placed an expansion coil spring 32. Thus, by the turning of the screws 31 and by the co-operating action of the springs 32, the conveyer members 23 and 24 are adapted to hold a row of nails therebetween, and they may be spaced from each other so as to accommodate therebetween nails of different thickness. It should also be observed that the wall portions 19 and 20 of the nail receptacle, by their attachment to the respective conveyer members, are adjustable therewith and adapted to form a longitudinal opening at the bottom of the nail receptacle in registration with the space between the conveyer members in order to accommodate the heads of the nails held in the nail conveyer.

Each of the conveyer members 23 and 24 is preferably curved, as viewed laterally and as shown in Figure 1, and a plate 33, extending over the conveyer members and corresponding in curvature with them, is secured to one of the members so as to be spaced from them sufficiently for allowing a free sliding of the nail heads between the plate and the conveyer members, while at the same time the plate prevents an upward discharge of the nails from the nail conveyer. To the plate 28 is secured an angle bracket 34, at one of its wings, and at its other wing the bracket is secured to the operating rod 12. The bracket thus supports the nail receptacle 18 and the nail conveyer 22 in inclined positions, so that nails or tacks 35, dropped into the receptacle and held between the conveyer members, as shown in Figure 3, may be moved by gravity toward the nail conveyer's free end, which, by the adjustable arrangement of the plate 28, is adapted to coincide with a portion of the frame 2 adjacent to the place of attachment for the stem 5 of the guide member 4.

At this portion the frame has secured thereto a cam plate 36, which is adapted to be engaged by a rocking, nail-holding element 37 pivotally secured within the conveyer member 24 and near to the free end of the nail conveyer, the end of the member 24 for this purpose being bifurcated and preferably also being recessed, so that a spring 38 may be secured by a screw 39 within the member in order to normally hold the element in a position for allowing nails to pass to the free end of the nail conveyer. The end of the screw 39 may extend outside of the member 24 so that

it abuts a recessed portion 40 on the rocking element for limiting the rocking movement of the element to this position, as shown in Figure 2.

5 A spring 41 is secured to the conveyer member 23 at a short distance from the free end of the nail conveyer. This spring is bent so as to extend transversely of the nail conveyer at its free end, as shown in Figures 2 and 3, so that, when a nail has passed through the nail conveyer to its free end, the spring 41 yieldingly retains the nail thereat, and the rocking element 37, may be provided with a somewhat V-shaped or cut-out portion 42, and 10 it is otherwise so shaped that by a sufficient rocking movement against the tension of the spring 38 the element is adapted to catch the nail at the free end of the nail conveyer in the portion 42 and therefore when the nail is 15 thus pressed against the conveyer member 23, it is held frictionally in the nail conveyer.

In Figures 2 and 3 the nail conveyer 22 is shown as converging with its free end toward the frame 2. Although this convergent 20 relation between the nail conveyer and the frame is not absolutely necessary for the operation of the nail setter 1, it is necessary that the frame and the nail conveyer be in a yielding relation to each other in order to allow 25 the rocking element 37 to be moved over the cam plate 36 on the frame. A convenient way of accomplishing this purpose is to cause the operating rod 12 to fit loosely in the openings 30 11 and the plates 9 and 10, as shown in Figure 35 2. The weight of the nail receptacle 18 and the nail conveyer 22, together with the weight of their attached parts, is then sufficient to hold the nail conveyer in the proper yielding relation to the frame 2 when the handle 3 40 thereof is in an upright or nearly upright position, which is the position mostly assumed during the operation of the nail setter. An adjusting screw 50 may be provided in the member 6 for bearing with its outer end upon 45 the supporting plate 28. This screw is easily adjusted so as to cause the rocking element 37 to engage the cam plate 36 with the required amount of pressure. However, the rod 12 may have a snug sliding fit in the opening 11, 50 and the frame 2 or the nail conveyer 22, or both, may be sufficiently springy to allow the element 37 both a rocking and a sliding movement over the cam plate 36.

The portion of the rocking element 37 that 55 contacts the cam plate 36 is preferably V-shaped, as shown at 43. By this construction the rocking element is forced to slide upon the cam plate when the nail receptacle and the nail conveyer are pushed from their normal 60 positions, in which they are held by the spring 15 on the operating rod 12, as shown in Figures 1 and 2, but is prevented from rocking by the engagement of the recessed portion 40 with the end of the screw 39. Again, as soon 65 as the spring 15 is allowed to move the oper-

ating rod 12 and therewith also the nail conveyer and the nail receptacle back toward their normal positions, the frictional engagement of the portion 43 of the rocking element 70 causes the rocking element to swing against the tension of the spring 38 to the nail-holding position shown in Figure 3, and the rocking element retains this nail-holding position so long as the operating rod 12, the nail receptacle and the nail conveyer are not again 75 moved in the direction away from their normal positions or to their normal positions, when the rocking element is allowed to slip out of engagement with the cam plate 36 and to assume its nail-clearing position, as shown 80 in Figure 2.

Preferably at the beginning of the curved portion of the nail conveyer the conveyer member 24 has secured thereto a bracket 44, which extends toward the bar 8 and has oscillatively secured thereupon a member 45 provided with an arm 46, which is adapted to be engaged by tripper bars 47 adjustably secured upon the bar 8. Upon the oscillative member 45 and on each side of the pivot 90 therefor is pivotally attached a block 48, and each block 48 has secured thereto one end of a bar 49. These bars 49 extend alongside of each other and transversely of the nail conveyer 22 and are adapted by the oscillative movement of the member 45 to slide alternately across the space between the conveyer members 23 and 24, so that, when the nail conveyer is in its normal position, as shown 95 in Figure 2, a row of nails 35 is retained in the conveyer by one bar, and, when the nail conveyer is moved from its normal position to the position shown in Figure 3, this bar is retracted and thereby releases the nail nearest thereto so as to allow the nail to move 100 by gravity toward the free end of the conveyer while the other bar retains the other nails in the conveyer. Into the bracket 44 is threaded a screw 51, which has a taper end adapted to extend between the bars 49, 105 and the conveyer member 24 has therein a cut-out portion 52, in which extends a spring 53 suitably secured to the bracket 44 and provided with arms terminating in portions that hook over the respective bars 49. This spring 110 115 is tensioned so as to draw the bars normally toward each other. The screw 51, acting against the tension of the spring 53, thus serves as a means for adjustably separating the bars 49 in correspondence with the thickness of the nails that pass through the nail conveyer.

In some instances it may be desirable to provide the nail receptacle with a cover 54, 120 and the cover may be secured to the nail receptacle in any approved manner. For example, it may have turned-over end portions 55 so as to adapt it to be sprung over the end walls 21 of the receptacle portion 19.

Before beginning the operation of the nail 130

setter 1 the operator adjusts the nail receptacle and the nail conveyer for the required thickness of nails and places a quantity of the nails 35 in the nail receptacle. On account of the convergent side walls of the receptacle the nails will be disposed to form a single row at the bottom of the receptacle and between the members 23 and 24 of the nail conveyer, the heads of the nails preventing the nails from falling through the conveyer. By means of the handle 3 the operator then places the nail setter in its desired position on an object and with his thumb depresses the plate or button 16, thereby moving the operating rod 12 forward and therewith also the nail receptacle and the nail conveyer. This motion causes the arm 46 of the oscillative member 45 to contact the forward tripper bar 47 and to be moved thereby, thus 20 retracting the forward bar 49 and allowing the nail 35 nearest thereto to pass to the free end of the nail conveyer, where it is retained by the spring 41. The rocking element 37 is thereafter operated so as to catch the nail and to hold it in the nail conveyer while the nail is set, as hereinbefore explained.

For some nail setting work the use of the guide member 4 is not required, and in such cases it may be removed from the frame 2. 30 However, it may expedite the nail setting to use the guide member, for instance, in connection with work on shoe soles, as indicated in Figure 2, and on other objects or whenever it is convenient to guide the nail setter along the edge or an object for setting nails at predetermined spots thereon.

Although in the foregoing I have described one embodiment of my invention, it is evident that the principle thereof can be embodied in other forms. I therefore reserve the right to make such modifications and changes as are in accordance with the spirit of the invention and come within the scope of the appended claims.

45 I claim:

1. In a nail setter adapted for setting nails at predetermined spots, a frame; a receptacle slidably mounted on the frame and adapted to receive nails therein; conveying means connected with the receptacle for leading the nails therefrom; and means adapted to engage the frame and to be actuated thereby when the receptacle is slidably moved for releasably holding a nail in the conveying means while the nail is set.

50 2. In a nail setter adapted for setting nails at predetermined spots, a frame; a receptacle slidably mounted on the frame and adapted to receive nails therein; a nail conveyer connected with the receptacle for leading the nails therefrom; means for allowing the passage of only one nail at a time through the nail conveyer to the free end thereof; means at the free end of the nail conveyer 55 for yieldingly retaining the nail passed

through the conveyer; and means adapted to engage the frame and to be actuated thereby when the receptacle is slidably moved for releasably holding the nail at the free end of the nail conveyer while the nail is set.

3. In a nail setter adapted for setting nails at predetermined spots, a frame; a nail conveyer comprising a pair of members slidably connected with the frame and adapted to be spaced from each other so as to hold a row of nails between them; means for spacing the conveyer members from each other so as to accommodate nails of different thickness in the conveyer; a nail receptacle comprising wall portions connected with the respective conveyer members so as to be adjustable therewith and adapted to form a longitudinal opening at the bottom of the receptacle in registration with the space between the conveyer members in order to accommodate the heads of the nails in the row between the conveyer members; means at the free end of the nail conveyer for yieldingly retaining the nails passed through the conveyer; and means adapted to engage the frame and to be actuated thereby when the nail conveyer is slidably moved for releasably holding a nail at the free end thereof while the nail is set.

4. In a nail setter adapted for setting nails at predetermined spots, a frame; a nail conveyer comprising a pair of members slidably connected with the frame and adapted to be spaced from each other so as to hold a row of nails between them; means for spacing the conveyer members from each other so as to accommodate nails of different thickness in the conveyer; a nail receptacle comprising wall portions connected with the respective conveyer members so as to be adjustable therewith and adapted to form a longitudinal opening at the bottom of the receptacle in registration with the space between the conveyer members in order to accommodate the heads of the nails in the row between the conveyer members, the nail receptacle and the nail conveyer being adapted to be held in an inclined position so that the nails may be moved by gravity toward the free end of the conveyer; a member oscillatively mounted on the conveyer; bars pivotally connected with the oscillative member and slidably mounted alongside of each other so as to extend transversely of the conveyer, the bars being adapted to slide alternately across the space between the conveyer members, so that, when the nail conveyer is in its normal position, the nails are retained in the conveyer by one bar, and, when the nail conveyer is moved from its normal position, this bar is retracted, and thereby releases the nail nearest thereto so as to allow the nail to move toward the free end of the conveyer while the second bar retains the other nails in the conveyer; means secured to the frame for operating the oscillative member when the

9. In a nail setter, a frame; a receptacle
slidably mounted on the frame and adapted
to receive nails therein; conveying means
connected with the receptacle for leading the
5 nails therefrom; a guide member secured to
the frame and adapted to engage the edge of
an object so that the nail setter may be moved
along the edge for setting nails at pre-
determined spots on the object; and means
10 adapted to engage the frame and to be actuated
thereby when the receptacle is slid for releasably holding a nail in the conveying
means while the nail is set.

10. In a nail setter, a frame formed with a
15 handle whereby the nail setter is adapted to
be moved manually for setting nails at pre-
determined spots on an object; a receptacle

slidably and adjustably mounted on the
frame and adapted to receive nails therein;
conveying means connected with the receptacle
20 for leading the nails therefrom; and
means adapted to engage the frame and to be
actuated thereby when the receptacle is slid
for releasably holding a nail in the conveying
means while the nail is set.

11. In a device of the type described a
receptacle for receiving loose nails, means
carried by said receptacle for arranging the
nails in a predetermined position, a nail positioner connected with said receptacle for
30 receiving the nails one at a time, and means
for feeding the nails one at a time, said means
agitating said receptacle.

EDWARD F. MALOUF.
